UNITED STATES PATENT OFFICE.

FRED HARRIS LYNDS, OF NORTH ATTLEBORO, MASSACHUSETTS, ASSIGNOR TO WHITING & DAVIS COMPANY, A CORPORATION OF MASSACHUSETTS.

MESH MACHINE.

Application filed October 24, 1924. Serial No. 745,602.

This invention relates to machines for making link mesh fabric, such as is commonly used in the manufacture of ladies' hand bags and other similar articles. More specifically, the invention is directed to the provision of a machine for the production of link mesh of an ornamental character containing links of different colored materials arranged in the fabric according to selected designs or patterns.

Machines of various types are in use at the present time for making link mesh, and these machines produce the mesh in the form of a cylindrical sleeve or in the form of a flat web or strip. The links of which the fabric is composed are usually made of wire of a precious or semi-precious metal, and in some of these machines the wire is led from a supply, usually in the form of a reel, to link forming tools in which suitable lengths of wire are severed and formed into rings which intermesh with those of the piece of mesh. In these machines the mesh and the link forming tools are given a step by step relative movement, and the tools operate to insert a link at each period of rest of this movement. Sometimes several sets of tools are used in a machine and these tools insert links in successive rows in the piece, but each operation of each set of tools forms but a single link. In such machines a single kind of wire is employed and the fabric produced has a plain undecorated appearance.

The machine of the present invention is designed to produce ornamental mesh and is arranged and constructed so that a plurality of supplies of different kinds of wire or of wires differing in surface appearance may be used, and so that links made of these different kinds of wire may be incorporated in the fabric as the mesh making operation progresses. An automatic control mechanism is employed which causes wire to be fed from the different supplies to the link forming tools in a predetermined order of succession, and various patterns may thus be formed in the fabric by links of contrasting colors.

The principles of the invention may be utilized in connection with mesh making machines of any of the various types now frequently used for the purpose. Among these machines are those in which the mesh is made in the form of a sleeve, others which make flat strip mesh, machines in which the

piece of mesh moves downwardly as it is formed, and machines in which the mesh has an upward movement relative to the link forming tools.

The type of machine which is considered best for the purpose of producing the ornamental mesh is that in which the mesh is made in the form of a sleeve and has an upward movement as successive links are added at the lower edge of the piece. This machine is provided with a plurality of supplies of different kinds of wire or wires presenting different surface appearances, and automatic mechanism for regulating the operation of the machine so that links are made from these wires in any predetermined order of succession, so that the machine will begin to make links of any of the wires at any predetermined point in its operation, and so that the shift from one wire to another may take place after any predetermined number of links has been completed. This automatic mechanism includes a master control device of such a construction that it may be used to produce any desired pattern, and when suitable adjustments have been made to produce such a pattern, a piece of mesh will be made in which the pattern is continuously repeated.

In mesh making machines of the sleeve type, the wire is fed from the supplies to link forming tools which make the rings and cause them to intermesh with rings at the edge of the piece of fabric. In the operation of the tools a piece of wire of the proper length is severed from the supply. This severed length is bent to form a staple, the staple is advanced toward the mesh so that its legs enter a pair of rings lying side by side at the edge of the mesh, and then the legs of the staple are bent so as to form a closed ring. Each of the supplies of wire is provided with its individual feeding device, and the control mechanism, the action of which is governed in accordance with a pattern causes one of these feeding devices to come into action whenever a link is to be formed by the tools, while the other feeding devices are held inactive.

The automatic mechanism which controls the action of the wire feeding devices is driven by the power driven mechanism of the machine and is timed so as to operate in correspondence with the step by step movement of the piece of mesh relative to the

2
 tools and the operation of these tools in the periods of rest of this step by step movement. This control mechanism governs the operation of the feeding devices and also governs the control of a device which serves to direct the wire being fed to the tools. This guiding device includes a movable block which has passages through it corresponding in number to the number of different supplies of wire. The wire coming from the supplies to the tools is led through these passages and when a particular kind of wire is to be fed the block will be positioned by suitable devices under the control of the master mechanism so that the passage in which that wire lies will be in registry with the tools. Consequently, when the feeding devices associated with the supply of that wire are actuated the wire will be directed properly so that the portion which is passed through the block will be in such position that it may be acted on by the tools. The master controller governs both the operation of the feeding devices associated with the several supplies of wire and also the position of the block above referred to, and at selected intervals the control mechanism functions to discontinue the operation of the feeding device associated with one supply of wire. It then brings into action the feeding device associated with another supply of wire, from which links are next to be made, and at the same time causes the block to be moved so as to place the passage for the wire which is to be fed thereafter opposite the feeding point of the tools.

This master control mechanism includes a pattern control device which determines the order of succession of the feed from the different supplies of wire, the times during the operation of the machine when the shift will be made from one supply to another, and the number of links which will be made from each supply before the shift is made to another supply. This pattern mechanism may have various forms, but one convenient form includes an element having a succession of pattern control areas mounted thereon. An endless chain may be used for the purpose, having pattern control blocks mounted on it at the desired intervals. This chain is carried by a support so actuated that the color control areas on the chain are brought successively into effective position to exercise their control over the wire feeding devices. The color control blocks on the chain are of different shapes, and there are blocks of as many different shapes as there are different kinds of wire to be used in the mesh. Controlled by the blocks is a member which is caused to assume different positions of rest, which are determined by the shape of the block which is in effective position. As the blocks are brought

successively into effective position, the member assumes a position of rest which is determined by the block then in place, and also actuates suitable means whereby one of the feeding devices will be made active while all the others are held inactive. Accordingly the shape of the block which is brought into effective position will determine from which supply of wire a link is to be made, and by properly arranging the blocks on the chain, mesh of any desired pattern may be produced. Instead of using a chain I contemplate the use of a rotary support having members of different shapes arranged in its periphery according to a selected pattern. These members may take the form of blocks or pins, having different heights, and these blocks would serve the same purpose as the blocks carried by the chain; that is, would determine the position of rest of the member which controls the action of the wire feeding devices. The use of the chain, however, is a convenient way of producing mesh in which the pattern is quite long. For this reason the chain offers some advantages over other similar devices which could be used for the purpose.

For the production of a mesh of intricate pattern it may be necessary to control the formation of each separate link in the fabric. Accordingly the control chain will have as many blocks as there are links in a complete figure of the pattern, and the blocks will be brought successively into operating position, one block per link. However, it is frequently desirable to produce mesh in which stripes or bands of a solid color occur. Such mesh can of course be produced by the use of a chain in the manner described, but whenever a band is being formed a long series of identical blocks appears in the chain. These blocks are brought successively into action, but no change in the action of the feeding devices occurs because the same wire is to be used throughout the series. Under these conditions, the pattern mechanism is actuated for each link without useful result and consequently the parts of the mechanism would become worn to no purpose. In order to avoid the repeated actuation of the pattern mechanism, when a long series of links are to be made from the same supply of wire, I provide a throw-off device which causes parts of the mechanism to remain stationary throughout such a succession of links. During this period of inoperativeness the wire feeding device associated with the supply from which the series of links is to be made, is continuously kept in operation. When the series of links has been completed the mechanism is again brought into action, and thereafter the single links of the mesh are controlled by the individual block on the chain.

Ordinarily whenever a long series of links of the same color is to be produced, this series will take the form of a row or a plurality of rows of links extending completely around or across the piece of mesh. Accordingly, the machine is usually arranged so that the throw-off device may be brought into action once per row. It may be desirable, however, to bring the device into action more frequently during the formation of the piece of mesh, and the arrangement is such that a long series of links of the same color can be formed as single rows, as parts of a row, or as a succession of complete rows and parts of others. The operation of the throw-off device relieves the pattern mechanism from wear during the times when control of the individual links is not desired, and since this throw-off is brought automatically into operation, in accordance with the pattern, the intervention of the operator is not required.

With the pattern mechanism of the type described, it will be seen that mesh having extremely intricate patterns may be produced and the figures which constitute a pattern may be repeated as many times as may be desired, with each length of mesh which contains a complete pattern a duplicate in all respects of all the other pieces. The length of the pattern, however, is practically unlimited and, as will presently be seen, the change from one pattern to another is a simple matter which does not require that the machine be idle for any considerable length of time. The machine provides the maximum degree of control over the formation of the links, and in addition includes mechanism by which the control may be exercised over the formation of groups of links as well as over single links.

In the accompanying drawings,

Fig. 1 is a top plan view of a machine constructed in accordance with the present invention, certain of the parts being shown largely in diagrammatic form,

Fig. 2 is a vertical, longitudinal section through the machine illustrated in Fig. 1,

Fig. 29 is a side view of a detail of the mechanism by which the wire feeding devices are controlled,

Fig. 30 is a view in side elevation of a modified form of wire feeding device,

Fig. 31 is a plan view of the same, with the upper feeding rolls removed,

In these drawings, the machine is seen to consist of a main bed 35, which is mounted on legs 36 in any convenient location. As illustrated in Fig. 4, the machine is mounted on a table 37, having legs 38 resting on the floor.

Mounted centrally of the bed 35 is a block 39 on either side of which are carried link forming tools. Two sets of tools are shown in use in this machine, and these tools operate simultaneously to produce links in successive rows. As will presently be described, the mesh is in the form of a sleeve, which is given a step by step movement relative to the tools. In the course

of this movement the mesh is moved upwardly so that the movement may be described as being spiral with respect to the tools. The tools form links of successive rows, so that upon each complete rotation of the sleeve of mesh, two rows of links will have been produced. As the formation of the support and the tools for producing the

mesh are, in general, similar to those shown in the Pratt Patent, No. 948,615, dated February 8, 1910, it is not necessary to describe these parts in any considerable detail.

Secured in the top of the block 39 is a ring 40, having a double spiral groove formed in its face. On top of the block 39 is an upper block 41, bolted in place, and a ring 42 runs freely in a channel formed in the face of the upper block resting on ball bearings which run on top of the ring 40. The ring 42 is formed with alternate vertical ridges and depressions in its outer face. Encircling the parts described is a sleeve 43, which is freely rotatable on the ball bearings on a support 44. This sleeve has its inner face provided with alternate vertical ridges and depressions and its upper end has a flange 45 which has teeth 46 formed in its edge. The sleeve is driven with a step-wise movement of rotation by means of a swinging pawl 46' carried on a vertical rod which is actuated by a cam 47 on the main cam shaft. As will be understood, the links in a piece of mesh tilt in opposite directions in alternate rows, and this slanting position of the links is taken advantage of in supporting and moving the sleeve. The double spiral groove in the ring 40 cooperates with the vertical ridges and depressions in the sleeve 43 so as to grip the links of the mesh quite securely and as the sleeve is given a rotational movement, as will presently be described, the mesh is caused to move about with the sleeve and to have an upward movement which is imparted to it by the spiral groove. The piece of mesh which is shown in dotted lines, as indicated at 47, extends below the end of the sleeve 43 and along this edge new links are added. The sleeve is given a step by step movement, such that the sleeve is advanced by the diameter of one link at each step, and during the periods of rest of this step by step movement the link forming tools operate to insert links at the edge of the fabric. The link forming tool assemblies are shown largely in diagrammatic form, as these devices are well known in the art.

The operating parts of the tools are driven by a main shaft 48 suitably supported in brackets beneath the bed of the machine, and this shaft carries bevelled gears 49, meshing with similar gears 50 on vertical shafts 51. The shaft 48 carries a pulley at one end with a suitable clutch mechanism 48', and at the other end is provided with a hand wheel so that the machine may be operated by hand, should it be necessary to insert one or more links at some point where links are missing from a piece of fabric. Each of the vertical shafts drives one of the tool assemblies, but one of which will be described since they are duplicates. Mounted on the vertical shaft 51 is a disc 52 carrying an eccentric pin 53

encircled by a roller. Mounted in a sliding block 54 which runs in guides carried by upright standards 55 mounted on the bed of the machine, is a plunger 56, carrying discs 57 which lie on either side of a cross piece 58 having a slot in which the roller 53 is received. As the shaft 51 rotates the eccentricity of the pin 52 causes the plunger to be reciprocated toward and away from the central block about which the sleeve of mesh is supported. This plunger consists of a cylindrical housing 59 in the forward end of which is mounted the plunger proper, which is made up of a cylindrical body 60 in which is threaded a tubular member 61. The free end of this tubular member carries a pair of prongs 62. Threaded in the member 59 is a die rod, the outer end of which is shown at 63, and the prongs on the member 61 are adapted to be spread apart by the end of the die rod when the die rod is moved relatively to the tubular member. The latter carries a depending lug 64, held in place by a lock nut. The tubular member 60 is held in place in the cylindrical housing 59 by spring means so that as the complete plunger assembly is moved toward the sleeve of mesh, the depending lug 64 strikes against a stop 65 carried on a guide block 66 in which the tubular member 61 is freely movable, but the die rod will continue to move so that the end carrying the die will be forced between the prongs 63.

Mounted in a suitable channel formed in the block 66 is a pin which carries a knife 67. This pin carries a lever at its outer end which is actuated by a swinging lever 68, shown in dotted lines in Fig. 2. The end of the lever 68 is moved by a vertically reciprocating lever 69 which is actuated by a cam 70 on the main cam shaft. The knife slides over the face of a feed block 71, shown more clearly in Fig. 26. The outlet end 72 of this feed block lies flush against the side of a channel formed in the block 66 and a leaf spring 73 mounted on the stationary block bears against the upper surface of the movable guide block. This guide block has three channels 74 formed in its surface, a portion of the channels being covered by a plate 75. At the rear end the block carries the ends of tubes 76, each of which is connected to one of the channels in the block at one end and at the other end to a part of one of the wire feeding devices. The wire is fed through these tubes from the supplies to the channels being delivered out into the slot in the block 66 by the operation of the feeding devices.

Also mounted in a channel in the block 66 is a pivoted lever 77, the rear end of which bears against the top of a rod 78, carrying a roller bearing against the surface of a cam 79 on the main shaft of the machine. The forward end of the rod 77 carries a mandrel

80. At the proper instant in the operation of the machine, wire is fed from one of the wire feeding devices, through its channel in the block 71. At this time the block 71 has been moved to such a position as to deliver the wire properly to the tools. This movement is brought about by the pattern control mechanism, as will presently be described. A length of the wire being fed is delivered 10 into the slot in the block 66 in front of the knife mechanism carried by the rod 67. The end of this wire bears against a spring-pressed stop 81. The knife is then rocked so as to sever the length of wire and the spring pressure of the stop holds it in place until it can be picked up by the tools. The knife now swings backwardly out of the way and the mandrel 80 comes into position behind the piece of wire. The plunger assembly of 15 the tools now moves forward, and the severed length of wire is formed into a staple by the coaction of the mandrel, the prongs, and the end of the die rod. This staple will be held in a suitable channel formed in the 20 face of the die rod the end of which has a semi-circular form corresponding to the shape to be given the staple. At the previous movement of the support, carrying with it the piece of mesh, the piece of mesh 25 is brought to rest in such position that a pair of links are in front of the legs of the staple and as the plunger assembly moves forward, carrying with it the staple, the legs of the latter are inserted through these links. 30 35. The staple must now be closed and this is effected by means of a die rod 82 mounted in a channel in the block 39. This die rod has a face which cooperates with the face of the outer die rod and when the two are forced 40 together the staple will be formed into a complete ring by their cooperation. The inner die rod 82 extends through the block with its rear end entering a channel in which moves a vertically reciprocating rod 45 83 which is raised and lowered by means of a cam 84 on the main shaft. At its upper end this rod has inclined surfaces 85 and as the rod is raised the inner die rod is forced outwardly into cooperation with the outer die rod. A spring 86 holds the rod 83 against the face of the cam, and the die rod is also provided with a spring which serves 50 to keep its rear face in contact with the inclined surface of the rod 83. 55. The parts which have now been described constitute the main features of the tool assembly, and two sets of these tools are employed in the present machine, inserting links at diametrically opposite points on the sleeve. The operation of the tools and the movement of the mesh support is properly timed so that during those periods when the mesh is moving the tools are inoperative and as soon as the sleeve of mesh has come to 60 rest the several parts of the tool assemblies 65 are brought into action in the proper timed relation. At each operation of the tools a single link is formed, but with two sets of tools this machine produces two links simultaneously. The two links are inserted in 70 successive rows, however, so that upon each complete rotation of the sleeve of mesh two complete rows of links will have been added to it. 75. As shown in Fig. 1, the present machine includes three different supplies of wire for each set of tools. The reels on which the wire is carried are not illustrated in the drawings, but the wire is led from these reels to the individual feeding devices, and 80 is thence fed to the feed block where it is delivered to the tools. The feeding devices are of similar construction and but one need be described. Such a feeding device is more clearly illustrated in Figs. 5, 6, and 7, where the feed block 71 is shown mounted in the block 66. Leading from the rear end of this block is the tube 76 previously described, and this tube leads to a standard 87 having a 85 central slot 88. A shaft 89 extends through the standard and carries a grooved roll 90 which lies in the slot 88. Above the roll 90 is a similar roll 91 carried on a shaft 92 which is held in bearings 93 movable in a slot formed in the upright. Springs 94 press 90 against these bearings and thus cause the rolls 90 and 91 to be held with their faces in contact. The depth of each groove is somewhat less than one half the diameter of one of the wires to be fed. Consequently 95 as a wire is led from the supply between the rolls the upper roll bearing against the lower roll by the spring pressure, will cause the wire to be firmly gripped. On the shaft 89 at one side of the block, is a spur gear 95, meshing with a similar gear 96 on the shaft 92. On the other end of the shaft 89 is a ratchet wheel 97 and swingingly mounted on the end of the shaft 89 beyond the ratchet 100 wheel is a lever 98 which carries a spring 105 pressed pawl 99. The lever 98 is connected by a link 100 to a bell crank 101, pivotally mounted in the bracket below the table. The other arm of the bell crank carries a roller 102, bearing against a cam 103 on the main 110 shaft, and this cam is designed so that upon each revolution of the main shaft the lever 98 will be rocked so that if the pawl 99 were free to do so, it would cause the ratchet to 115 be advanced by one step. The diameter of the wheels 90 and 91 and the size of the ratchet teeth, are such that one movement of the ratchet will cause a length of wire sufficient for a single link to be fed by the rolls. Mounted in a slot in the upright 87 is a rod 104, carrying a pin 105 which lies beneath the pawl 99. This rod terminates in an enlarged portion 106 which passes through a bore formed in the table and at its lower end bears against a control bar 120 125 130.

107, the construction and operation of which will presently be described. This control bar, however, is provided with notches 108, into which the pointed end of the portion 106 enters, and when the bar is in such position that the pointed end of the portion 106 enters a notch, then the pin 105 will be free of the pawl and the latter may drop down and engage the ratchet. When the bar 107 is so placed that no notch lies beneath the rod, then the latter is held upwardly in such a position that the pin 105 lifts the pawl clear of the ratchet. A feeding device similar to that described is provided for each supply of wire. Each of these feeding devices is provided with actuating means such as the bell crank 101, and the cam 103 which causes the lever 98 to be swung each time a length of wire is to be fed. Only one of these feeding devices will be rendered operative at a time and the feeding device which is to be effective to feed wire is determined by the position of the control bar 107. The latter is moved to different positions by the pattern mechanism.

Mounted on the forward end of the machine is a frame 109 which carries the mechanism by which the feeding of wire from the different supplies in a selected order of succession is brought about. A front elevation of the mechanism is illustrated in Fig. 4. At the left hand side of the frame there is mounted a wheel 110, having a groove formed in its periphery. This groove 111 as shown in Fig. 18, is formed to receive the links of a chain 112, and the chain carries blocks of three different kinds. The first of these, 113, has a raised portion 114 near one end thereof, and another flat portion 115 along the side of the raised portion. The end of the raised portion 114 and the flat portion 115 serve to determine the position of rest of an element which, in turn, controls the wire feeding devices and the arrangement of these surfaces, as shown in Fig. 13, corresponds to the feeding of one of the different kinds of wire. The block 116 has a central raised portion, the end of which has a greater area than the end of the raised portion 114 on the block 113. This type of block corresponds to the feeding of a different kind of wire. The third type of block 117 has a flat portion 118 and a raised portion 119, but these parts have an arrangement opposite to that in the block 113. Since this machine is to feed three different kinds of wire, three different types of block are employed, as described, but if a greater number of kinds of wire were to be used in the manufacture of the mesh then blocks of other shapes would also have to be employed; one for each kind of wire to be used. In Figs. 14 to 16 there are illustrated face views of the block and in Fig. 17 a sectional view. It will be seen that the raised portion

119 of the block shown in Fig. 17 has inclined edge surfaces 120, the purpose of which will be presently explained. The wheel 110 provides a support for the chain and the formation of the groove in the edge of the wheel insures that the chain will be fed positively and that the chain will be held against slipping so that the blocks may be suitably positioned with reference to other parts of the mechanism.

Mounted on the main shaft 48 of the machine is a spur gear 121 which drives a gear 122 mounted on the stud in the bracket. This gear drives another gear 123, shown more clearly in Fig. 8. The gear 123 is mounted on a stud 124, also secured in the bracket 109. Keyed to the stud 124 is a double surface cam 125, and in a cam channel 126, formed in this cam, runs a wheel 127 mounted on a plate 128. This plate has a pair of longitudinal slots through which are received bolts 129 by which the plate is mounted for sliding movement with reference to the frame 109. The plate is provided with a spring 130, which holds the cam roller 127 against the face of the cam. Mounted on the upper face of the plate is a spring-pressed pawl 131 which engages the teeth of a ratchet wheel 132, which is mounted on the stud supporting the wheel 110. This ratchet wheel 132 is fast on the wheel. As the main shaft of the machine rotates, it drives the gear 123 at the same rate of speed and consequently the cam rotates once per revolution of the main shaft and causes a reciprocation of the bar 128 and the advance of the ratchet wheel 132 once per revolution of the main shaft. As the link forming tools are operated at each revolution of the main shaft, it follows that the ratchet wheel is advanced one step per link. The ratchet wheel is so proportioned that at each step two links of the chain are fed forward. The chain, as shown in Fig. 13, carries a block on every other link. Consequently a new block is brought into position whenever a link is formed. Each block controls the formation of a single link in the mesh, and the shape of the block which is brought into effective position by the step-wise rotation of the ratchet wheel 132 will determine from which of the supplies of wire a length of wire for one link is to be fed.

Mounted below the table is a curved tube 133 into which the slack of the chain, diagrammatically indicated at 134, is received. The chain enters this tube, which is of considerably greater diameter than the chain and the slack piles up within the tube. The chain is endless, and passing out of the lower end of the tube 133 it is led upward and through a guide tube 135 which is suitably mounted on the frame 109 so as to guide a stretch of the chain directly to the wheel 110. With such an arrangement, an ex-

tremely long chain may be employed without inconvenience, since the slack of the chain is received in the tube 133 and is thus kept from injury and also prevented from 5 tangling. The use of such a long chain makes it possible to produce an intricate pattern in the mesh, as will be seen from the further description of the pattern mechanism.

10 Mounted in a suitable bracket 136, extending outwardly from the face of the frame 109, is a slide 137 which has dove-tailed edges 138 which enter suitable guide-ways formed in the bracket. Beneath the slide is 15 a roller 139 mounted on a stud, this roller entering a channel 140 formed in the double cam 125. These parts are shown more clearly in Fig. 8, and the channel 140 is so formed that the slide 137 is moved toward and away 20 from the face of the frame 109 at each revolution of the stud 124. The double cam is keyed to this stud, as is also the gear 123. Mounted in a housing 141 extending upwardly from the slide, is a pair of feelers 25 142 and 143. These feelers are placed one above another and have recesses formed in their opposed faces through which extends a pin 144, on which is pivotally mounted a lever 145, which is pivoted, as shown in Fig. 30 11, to each of the feelers. The forward ends of the feelers 146 are placed so as to bear against the color areas on the blocks and as shown in Fig. 11, a block similar to 113 is in registry with these feelers. The upper 35 feeler bears against the end of the raised portion 114, while the lower feeler bears against the surface 115 of this block. As the slide 137 is moved toward and away from the face of the frame 109, by the action of 40 the cam channel 140, the ends of the feelers bear against the inclined surfaces 120 formed on the blocks, and the position of the feelers relative to the housing 141 is thus determined by the shape of the blocks. When the 45 slide is being reciprocated so that the feelers are clear of the blocks on the chain, the chain will be advanced by one block. Then the slide is moved back and the feelers bear against the surface of the block, assuming 50 positions of rest which are determined by the shape of the block. The position of these feelers also determines the position of the lever 145, which is centrally pivoted on a fixed pivot and may be swung on this pivot by the relative movements of the feelers.

55 Mounted in the slide 137 is a second slide 147, having the shape of an open center frame. This second slide is shown more clearly in Figs. 20 to 22. Extending across the open center of this frame are screws 148 which bear against the lower end of the lever 145, and provide a means of fine adjustment. As the feelers move to different positions determined by the shape of the blocks, the lever 145 is swung to different positions and

in turn moves the slide 147. This slide moves transversely of the main slide 137, being guided by suitable guide members 149 formed in the main slide. At its rear end the slide 147 has an extension 150, the rear edge of which is formed with incised corners. Mounted in suitable guide-ways in a rearward extension from the main frame are 70 slides 151 and 152 and pivotally mounted above the extension from the frame is a lever 75 153 which has rollers 154 entering recesses in the slides 151 and 152. The slides 151, 152 lie on either side of the central pivot of the lever 153. At their forward ends the slides have step-like recesses 155 which are intended to cooperate with the corners of the extension 150 on the slide. As the slide 147 is placed in different transverse positions of adjustment, it will in turn determine the relative positions of the slides 151 and 152, 80 and the relative positions of these slides will, in turn, determine the position of the lever 153.

85 As the main slide, carrying the smaller slide 147, is reciprocated toward and away from the face of the frame by the cam 125, the feelers 146 will bear against the blocks on the color chain. These feelers will assume different positions which will, in turn, determine the position taken by the lever 90 145. The latter will thus move the slide 147 to different positions of adjustment transversely of the main slide and at the end of the movement of the main slide toward the frame 109, the extension 150 on this smaller 95 slide will bear against the slides 151, 152. In Fig. 20 the slide 147 is in a position corresponding to the position of the feelers, as determined by a block 113. As seen in Fig. 11, such a block causes the lever 145 to take 100 the position with its lower end swung to the left. This corresponds to a shift of the small slide 147 upwardly, as shown in Fig. 20. Accordingly, when the extension bears against the slides 151, 152, the slide 151 is 105 moved to the right, as seen in Fig. 20, while the slide 152 is moved to the left. The lever 153 is thus swung with its upper end moved to the right. In Fig. 20 the slide 147 lies in the position such as it would receive by 110 the contact of the feelers with the block 116. The slide is now centrally positioned and both slides 151 and 152 lie with their ends even. In Fig. 22 the slide 147 lies in a position such as it would receive by the contact of the feelers with the block 117. The slide has been moved to a position opposite to that shown in Fig. 20, and now the upper slide 151 lies in the extreme forward 115 position and the lower slide 152 lies in the extreme rearward position. The lever 153 has been swung with its upper end as far forward as possible.

120 Mounted in a suitable channel beneath the table, and supported by brackets 156, is the 130

control bar 107. At its forward end the bar has downwardly extending lugs 157 between which is received a roller 158 on the upper face of the lever 153. As the lever 153 is 5 swung by the relative movements of the slides 151 and 152, the bar 107 will be given different longitudinal positions of adjustment. It will be seen that the mechanism is such that the shape of the blocks on the 10 color chain will determine the position of adjustment given this bar. In the present machine two sets of link forming tools are employed, and a single control mechanism controls the wire feed to each of these sets 15 of tools. This construction is not essential, since it is possible to provide separate pattern mechanism for each set of tools so that the feeding of the wire to different tools would be individually controlled. In the 20 present instance, however, both sets of tools are simultaneously fed with the same kind of wire, but from different supplies. Accordingly, the single pattern mechanism controls the feed from two different groups of 25 wire supplies, and two control bars 107 are provided, connected together by a rod 159. The control bars have notches 108 formed in their upper surfaces and the enlarged extensions 106 of the rods 104 bear against the 30 upper surface of the control bar. The bar 107 is capable of being placed in three different positions of adjustment, according to which of the three different blocks are in position. In each such position of adjustment 35 one of the notches lies beneath the portion 106 of one of the rods 104. When that rod drops down its pin 105 clears a pawl on one of the wire feeding devices and accordingly that wire feed is brought into action. Thus 40 the different positions of adjustment of the bar, as determined by the blocks on the chain, result in one of the wire feeding devices being rendered effective, while the others are maintained out of action, and the arrangement of the notches 108 in the bar is such 45 that but one feed mechanism is effective at a time. Mounted underneath each branch of the control bar is a small cam plate 160, having areas as shown in Fig. 29, of three different heights. A lever 161, pivotally 50 mounted beneath the bed of the machine, has a roller at one end which bears against these surfaces. At its other end the lever supports a rod 162, which extends upwardly through a bore formed in the frame, and through the block 66. The movable wire block 71 has a downwardly extending rod 163 which enters a bore in the block 66 and rests against the upper end of the rod 162. The arrangement is such that as the control bar is shifted longitudinally to the different positions of 60 adjustment, the cam plate will cause the lever 161 to be swung on its pivot, the extent of the swing being determined by the height 65 of the surface against which the roller bears.

In such swinging movement the wire block 71 will be given different positions of rest, and the parts are designed so that when a notch 108 is under one of the rods 104 so as to cause wire to be fed from the supply at 70 the same time the wire block 71 will be positioned by the cam plate 160 so that wire from that supply will be properly delivered to the link forming tools. The positions of rest of the bar 107 thus determine not only which of 75 the wire feeds will be effective, but also cause the wire guide block to be properly positioned so as to deliver this wire to the tools. Accordingly, the shape of the blocks on the color chain exercise control both over 80 the feeding of wire and the guiding of the wire being fed to the tools.

With the mechanism so described, the color chain is advanced one step, or one block, each time a link is formed. Each 85 block on the chain thus determines the kind of wire which is to be used in a single link. Referring to Fig. 28, in which there is shown diagrammatically, a piece of pattern mesh, the light links, designated by A may be 90 made of any of the three kinds of wire arranged according to a selected pattern. However, the pattern which is to be produced in the mesh may require the formation of a single row of links B, all of which 95 have the same color. Such a row of links across the piece of mesh could be produced by the use of a chain in which there was a succession of blocks all of the same kind, corresponding to the kind of wire to be used 100 in this row, but during the manufacture of this row the pattern mechanism would be actuated each time a link is formed but since the blocks were all alike no change in the position of the control bar would follow. 105 The actuation of the pattern mechanism, therefore, would not produce any useful result, and it is desirable to avoid needless wear on the pattern mechanism which would result from such a situation. It also may be 110 desirable to produce a mesh in which there appears a strip or band, indicated as C—D, made up of a plurality of links of the same color. This is simply an exaggerated case 115 of the same kind as that previously described, and if the color chain were to control the formation of each link a long succession of blocks, all of the same kind, would appear on the chain and the pattern mechanism would be actuated each time, but without change in the position of the control bar. 120 It is desirable to arrange the mechanism so as to permit a single row, a part of a row, or a series of rows, to be made up of links of the same kind of wire without the necessity 125 of bringing the pattern mechanism into action for each link of this series. The present pattern mechanism is arranged so as to permit the mechanism to be held at rest at selected intervals, corresponding to the for- 130

mation of groups of links, as above referred to. This requires the use of a throw-off device which holds the color chain stationary during the formation of the group of links referred to.

- Such throw-off mechanism involves the use of a cam 164 on the main cam shaft. Loosely mounted on an auxiliary shaft 165, suitably supported in the frame 109, is a lever 166 which carries at its end a spring-pressed pawl 167. A ratchet wheel 168 mounted loosely on the shaft 165, is positioned so as to be engaged by this pawl, and a disc 169 of the type shown in Fig. 25, is also mounted loosely on the shaft 165, but is rigidly connected to the ratchet 168. The cam 164 has one high spot which causes the lever 166 to swing, in turn causing the pawl to move the ratchet forward by one step. The ratchet has as many teeth as there are links in a row around the sleeve of mesh, and accordingly, as the ratchet is stepped forward once upon each revolution of the main drive shaft; that is, once for each link, it follows that the ratchet wheel and the disc 169 make one revolution upon the completion of a row of links. Mounted on a suitable projection from the frame 109 is a swinging lever 170, having a projection 171 which bears against the rim of the disc 169. This lever is spring-pressed so the projection will be held against the surface of the disc. Mounted fast on the shaft 165 is an arm 172, bearing against a cam 173 on the main cam shaft. At the other end of the shaft 165 there is rigidly secured an arm 174, carrying a spring-pressed pawl 175 at its outer end. This pawl has a rod 176 extending upwardly from its upper end, and a rod 177 extending from the lever 170 engages against this rod 176. When the lever 170 is in its extreme outermost position, the rod 177, bearing against the rod 176, holds the pawl out of engagement with the teeth of a ratchet wheel 178 mounted loosely on the shaft 166. When the lever 170 is allowed to swing inwardly, the rod 177 clears the rod 176, the pawl bears against the surface of the ratchet and becomes effective to move the latter. Rigidly secured to the face of the ratchet is a plate 179 of the type shown in Fig. 24, this plate serving as a control plate. The plate has depressions 180 formed in its surface. The plate 169 also has a single depression 181 formed in its surface, into which may be received the projection 171 on the end of the lever 170.
- With this arrangement it will be seen that the lever 172 will be actuated once on each revolution of the cam 173 on the main cam shaft. This will cause the shaft 165 to be rocked, swinging the arm 174 which carries the pawl. The lever 166 is also actuated once per link and, as previously described, causes a rotation of the disc 169

once per rotation of the sleeve of mesh; that is, once per complete row. As shown, the disc 169 has a single notch in its rim, and whenever the movement of the ratchet 168 brings this notch into position in front of the projection 171, on the lever 170, the latter is swung on its pivot and the rod 177 is cleared from the rod 176 and permits the pawl 175 to bear against the teeth of its ratchet 178. When this occurs the next movement imparted to the lever 166 by the cam 164 will result in the ratchet 178 being advanced by one step. In the construction described, since there is a single notch in the rim of the disc 169 and this notch comes into effective position once per row of links, the ratchet 178 with its disc 179 will be advanced one step per row of links in the piece of mesh.

The disc or plate 179 has depressions or notches formed in its surface and mounted in suitable brackets from the lower edge of the frame 109, is a rod 182 which carries an arm 183, the upper end of which bears against the surface of the disc 179. A spring 184 encircling this rod tends to swing it so that the end of the lever 183 is always in contact with the surface of the plate 179. At its other end the rod 182 carries an upright lever 185 which is intended to cooperate with a projection 186 on the lower face of the plate 128. The construction of the parts is such that whenever the plate 179 is moved so that a notch 180, or a depression 187 corresponding to a series of notches, comes beneath the end of the lever 183, the latter will swing upwardly, causing the rocking of the shaft 182. This will, in turn, cause a swinging movement of the lever 185 and the lever will swing to a position in front of the projection 186. The movement of the plate 128 to the right, as viewed in Fig. 4, is brought about by spring means. Accordingly, when the arm 185 moves to a position in front of the projection 186, the plate 128 is held stationary and the cam which ordinarily causes the reciprocation of this arm is without effect. Since the ratchet 132 is actuated by a pawl carried on the plate 128, when the plate remains stationary the ratchet receives no movement. Accordingly, the chain is held stationary and the same block on the chain will remain in effective position during the formation of a plurality of links. In the form of machine illustrated, the plate 179 which may be described as a control or throw-off plate, is given one step in its rotation for each complete row of links which is produced. This is because of the fact that the plate 169, which may be referred to as a selector plate, has but a single notch in its periphery, each of these notches corresponding to a forward step of the ratchet which moves the throw-off plate. Thus, whenever the throw-off plate presents

a notch 180 to the lever 183, the color chain will remain stationary throughout the formation of a row of links, so that all of the links of the row will be made of wire which is determined by the shape of the block which is in effective position when the color chain comes to rest. As soon as a high part of the plate 179 comes beneath the lever 183, the color chain again comes into action and is advanced one block for each link of the mesh. Whenever a depression, such as 187, of the throw-off plate is presented to the lever 183, then the color chain will remain stationary throughout the formation of a series of rows, the number of which will be determined by the length of the depression. Thus, by suitably forming the control plate, the mesh may be given stripes formed by a single row or groups of rows of the links of the same color, and the width of these stripes will be determined by the length of the depressions in the plate. As illustrated, the throw-off plate is brought into action by a single notch in the selector disc and the parts are timed so that the throw-off mechanism will become effective once per row. If desired, however, the selector disc could have a plurality of notches, in which case a single notch in the throw-off plate corresponding to one forward step in its rotation, would, in turn, correspond to the formation of a lesser part of a row. For instance, if the selector disc had two notches formed in its periphery, then a single notch in the throw-off plate would result in the formation of half a row of links of the same color and consequently, by suitably designing and timing the selector disc, the throw-off plate, and the color chain, it is possible to produce mesh in a wide variety of patterns and the mesh may have intricate patterns in which each single link being formed may be controlled, followed by bands or stripes of a solid color, or if desired, it may have a succession of bands of solid color so that each block of the chain, instead of corresponding to the formation of a single link, will correspond to the formation of a row of links. The throw-off mechanism, therefore, permits the action of the color chain to be modified so that a single block governs the feeding of wire for one link, a part of a row, a full row, or a succession of full rows. In the machine described the single pattern mechanism controls the feeding of wire to two sets of tools. It will be evident that separate pattern mechanism could be provided for each set of tools and that instead of feeding three different kinds of wire, a less or greater number could also be fed in a predetermined order of succession. If links were to be formed of wire of four different kinds, this would require that four different kinds of blocks would be used on the color chain; also that the control bar would have four notches instead of three,

and that the cam plate on the color bar would have four different cam surfaces instead of three. Various other minor changes would also be required in the mechanism.

It will be seen that the present mesh machine offers numerous advantages over those previously used for the production of an ornamental mesh, since it permits mesh to be made in which each single link is under control and also permits the action of the color controlling members to be multiplied so that instead of controlling a single link each member controls the formation of a group of links. By means of the throw-off mechanism, the pattern devices are relieved from needless work, and wear is thus reduced. It is evident that such a machine as this permits mesh to be made in an extremely wide variety of patterns, and since the color chains, the throw-off plates, and selector discs may be quickly changed, the change in the operation of the machine from one type of mesh to another does not result in any considerable delay.

While I have described the use of a color chain on which color control areas are provided, it is also possible to make use of discs having radial projections such as are shown in the co-pending application of Oscar Soderstrom, Ser. No. 672,271, filed Nov. 2, 1923. Such a plate, however, would ordinarily be used for somewhat less involved patterns than the chain is capable of making.

In the construction illustrated, I have shown the use of three different supplies of wire, each of which is provided with its individual feeding device. These supplies are in the form of reels which are conveniently mounted at one side of the machine. In front of each reel is a feeding mechanism of the type described, and the wire is led from the feeding mechanism through suitable tubes to the movable guide block. In the arrangement shown the reels are placed side by side along one side of the machine and the wire led from the feeding devices to the central block has to pass through tubes which have a curved shape. With some types of wire the bending of the wire necessary to cause it to move through the tubes may result in the wire being given a set which might result in the links formed of the wire opening slightly after they were incorporated in the piece of mesh. In order to avoid any difficulties which would result from the links thus opening, I have devised the wire feeding mechanism illustrated in Figs. 30 and 31. In Fig. 31 there are shown a plurality of feeding devices, here three in number, which are placed in series instead of lying side by side. These feeding devices correspond in construction to those previously described and are actuated in the same way by swinging arms 98 actuated by links 100 connected with levers 101 similar

to those shown in Fig. 5. Each of the wire feeding devices includes pairs of rolls mounted on shafts similar to shafts 89 and 92, the rolls being driven by means of gears 95 and 96, as before. The rolls lying between the upward extensions from the block 87 are arranged so that the three wires may be fed side by side. As shown in Fig. 31, the first pair of rolls 188 lies in the extreme upward position at one side of the space between the supports formed in the block 87. The second pair of rolls 189 lies in extreme lower position, and the third pair 190 lies in an intermediate position. The rolls are quite narrow and a space is left between the surface of the rolls and the edges of the support. With this arrangement it will be seen that three wires 191 may be fed between the shafts of each pair of rolls side by side, but only a single wire is engaged by each of the pairs of rolls. With this arrangement the feeding devices are placed directly behind the wire blocks and the reels from which the wire is drawn are placed beyond the feeding devices, preferably in such an arrangement that the wire may be led without bending from the reels to the feeding devices. The actuation of the feeding devices is controlled in the manner previously described, and for the formation of a single link but one of these devices will be active. Assuming that the rolls 188 are active, the wire will be fed forward between the shafts carrying the rolls 189 and 190 but the wire will be clear of these rolls and may be at once delivered into a tube which passes direct to the feed block without any intermediate bends. This arrangement prevents the wire receiving a set which might be detrimental in some instances with respect to the quality of the links produced from it. In general the operation and control of the wire feeding devices is similar to that previously described.

45 I claim:

1. A machine for making link mesh comprising the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of the supplies, for feeding wire therefrom to the link forming tools, and means for controlling the action of the wire feeding devices to cause the wire to be fed from the supplies in a predetermined order of succession and including a pattern control member having effective areas arranged thereon in accordance with a predetermined pattern, actuating means for bringing these areas successively into position as each link is formed, and automatic means for rendering the actuating means in-

effective throughout the formation of a group of links, the said automatic means including a member continuously advanced step by step, one step as each link is formed.

2. A machine for making link mesh comprising the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of the supplies, for feeding wire therefrom to the link forming tools, and means for controlling the action of the wire feeding devices to cause the wire to be fed from the supplies in a predetermined order of succession and including an element having a succession of pattern control areas disposed thereon in accordance with a predetermined pattern, a member brought into contact with successive areas and movable to different positions of rest determined by said areas, the said member being operable in each such position to cause one of the wire feeding devices to feed wire while the others are held out of action, actuating means for bringing the color control areas successively into effective position to control the position of rest of said member, this actuating means operating once each time a link is formed, and means operated by the power driven mechanism for throwing off the actuating means, whereby a single area controls the formation of a plurality of links.

3. A machine for making link mesh comprising the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of the supplies, for feeding wire therefrom to the link forming tools, and means for controlling the action of the wire feeding devices to cause the wire to be fed from the supplies in a predetermined order of succession and including an element having a succession of pattern control areas formed thereon in accordance with a predetermined pattern, actuating means for moving this member to cause the areas to be brought successively into effective position, one for each link being made in the mesh, a member brought into contact with the areas successively and movable to different positions of rest as determined by the area which is in effective position, this member in turn rendering one of the wire feeding devices operative while the others are held inactive, a throw-off device for rendering the actuating means inoperative throughout the formation of a plurality of links.

- links, and means operated by the power driven mechanism for bringing the throw-off device into action at selected intervals.
4. A machine for making link mesh comprising the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of the supplies, for feeding wire therefrom to the link forming tools, means for controlling the action of the wire feeding means to cause the wire to be fed to the tools in a selected order and at intervals, and automatic mechanism operative to alter the functioning of the control means to vary the said intervals.
- 20 5. A machine for making link mesh comprising the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of the supplies, for feeding wire therefrom to the link forming tools, an element having pattern control areas disposed thereon in a predetermined order of succession, means for causing these areas to control the action of the wire feeding devices to cause the wire to be fed to the tools in a predetermined order of succession, means for bringing the pattern control areas into effective position, one for each link being added to the mesh, and means for causing a plurality of links to be produced under the control of a single control area, the means last named including a member continuously advanced with a step-by-step movement, one step for each operation of the link-forming tools.
- 45 6. A machine for making link mesh comprising the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of the supplies, for feeding wire therefrom to the link forming tools, an element having pattern control areas disposed thereon in accordance with a predetermined pattern, means including a member brought into contact with these areas for causing a selected wire feeding device to become operative while the others remain inoperative, actuating means for causing the areas to be brought successively into operative position in correspondence with the operation of the link forming tools, and automatic means for controlling the action of the actuating

means to cause a selected area to control the formation of a group of links of predetermined number, the said automatic means including a member continuously advanced with a step by step movement, one step for each operation of the link forming tools.

7. In a machine for making link mesh, the combination of a support for a piece of mesh, link forming tools, means for actuating the tools to add links to the piece of mesh, a plurality of supplies of wire, a plurality of devices, one for each supply, for feeding wire from the supplies to the link forming tools, pattern control means actuated in accordance with the operation of the link forming tools for controlling the action of the wire feeding means to cause the wire to be fed to the tools from the supply in a predetermined order of succession, and an automatic throw-off device for modifying the action of the pattern control means to cause a succession of links to be made of wire drawn from a single supply, the said throw-off device including a member continuously advanced with a step by step movement, one step for each operation of the link forming tools.

8. A machine for making link mesh which comprises the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of these supplies for feeding wire therefrom to the link forming tools, a movable guide block having passages therethrough for each of the wires, means for positioning this block with one or the other of its passages in registry with said link forming tools, means for controlling the action of the wire feeding means and of the said positioning means to cause the wire to be fed to the tools in a selected order and at intervals, and automatic mechanism operative to alter the functioning of the control means to vary the said intervals.

9. A machine for making link mesh comprising the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of the supplies, for feeding wire therefrom to the link forming tools, and means for controlling the action of the wire feeding devices to cause the wire to be fed from the supplies in a predetermined order of succession and including an element having pattern control areas disposed thereon in accordance with a predetermined pattern, and automatic means for selectively causing

- these pattern control areas to be brought into action in accordance with the formation of single links and in accordance with the formation of groups of links, the said automatic means including a member continuously advanced with a step-by-step movement, one step for each operation of the link-forming tools. 5
10. A machine for making link mesh comprising the combination of a support for a piece of mesh, link forming tools, power driven mechanism for giving the tools and the piece of mesh a step by step relative movement and for operating the tools in the 10 periods of rest of this movement, a plurality of supplies of wire, a plurality of devices, one for each of the supplies, for feeding wire therefrom to the link forming tools, and means for controlling the action of the 15 wire feeding devices to cause the wire to be fed from the supplies in a predetermined order of succession and including an element having removable pattern control members of different kinds arranged thereon according to a predetermined pattern, and means 20 for selectively causing these pattern control members to govern the formation of single links and of groups of links, the means last named including a member continuously advanced with a step-by-step movement, one step for each operation of the link-forming tools. 25
11. A machine for making link mesh comprising the combination of a support for a piece of mesh, link forming tools, power driven mechanism for giving the tools and the piece of mesh a step by step relative movement and for operating the tools in the 30 periods of rest of this movement, a plurality of supplies of wire, a plurality of devices, one for each of the supplies, for feeding wire therefrom to the link forming tools, and means for controlling the action of the 35 wire feeding devices to cause the wire to be fed from the supplies in a predetermined order of succession and including an element having removable pattern control members of different characteristics arranged thereon according to a predetermined pattern. 40

in each such position operable to render a single wire feeding device effective while the others remain inactive, actuating means for moving said element to cause the pattern control areas to be brought successively into position, one area for each link being added to the mesh, a throw-off device for rendering the actuating means ineffective, and means operated by the power driven mechanism for controlling the action of the throw-off mechanism.

16. A machine for making link mesh comprising the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of the supplies, for feeding wire therefrom to the link forming tools, and means for controlling the action of the wire feeding devices to cause the wire to be fed from the supplies in a predetermined order of succession and including an element having pattern control areas arranged thereon according to a predetermined pattern, a member movable to different positions of rest determined by said areas and in each such position operable to render a single wire feeding device effective while the others remain inactive, actuating means for moving said element to cause the pattern control areas to be brought successively into position, one area for each link being added to the mesh, a throw-off device for rendering the actuating means ineffective, and means operated by the power driven mechanism for bringing the throw-off mechanism into action at intervals corresponding to the completion of a group of links.

17. A machine for making link mesh comprising the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of the supplies, for feeding wire therefrom to the link forming tools, and means for controlling the action of the wire feeding devices to cause the wire to be fed from the supplies in a predetermined order of succession, and including an element having a succession of pattern control areas arranged thereon in accordance with a predetermined pattern, a member having different positions of rest and in each such position serving to render one of the wire feeding devices operative while the others remain inoperative, actuating means interposed between the element and the member to move the latter to its different positions of rest as determined by the control areas on the

element, means for moving the element with a step-wise movement to bring the areas thereon successively into registry with the actuating means, the steps in this movement corresponding to the operations of the link forming tools, and automatic means actuated by the power driven mechanism of the machine for rendering the moving means inoperative at selected intervals and for periods of predetermined duration.

18. A machine for making link mesh comprising the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of the supplies, for feeding wire therefrom to the link forming tools, and means for controlling the action of the wire feeding devices to cause the wire to be fed from the supplies in a predetermined order of succession, and including an element having a succession of pattern control areas arranged thereon in accordance with a predetermined pattern, a member having different positions of rest and in each such position serving to render one of the wire feeding devices operative while the others remain inoperative, actuating means interposed between the element and the member to move the latter to its different positions of rest as determined by the control areas on the element, means for moving the element with a step-wise movement to bring the areas thereon successively into registry with the actuating means, the steps in this movement corresponding to the operations of the link forming tools, a throw-off device actuated by the power driven mechanism for rendering the moving means inoperative during periods corresponding to the formation of groups of links, and means for bringing the throw-off device into action at selected intervals.

19. A machine for making link mesh comprising the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of the supplies, for feeding wire therefrom to the link forming tools, and means for controlling the action of the wire feeding devices to cause the wire to be fed from the supplies in a predetermined order of succession, and including a chain having color control blocks of different kinds arranged thereon in accordance with a predetermined pattern, a member movable to different positions of rest and in each such position effective to render one of the wire feeding devices operative while the others

remain inactive, actuating means connected with the member and operable to move the latter to its different positions of rest under the control of the blocks on the chain, means for advancing the chain with a step by step movement in correspondence with the formation of individual links of the mesh, the blocks on the chain being successively brought into effective position with respect to said actuating means, and means for rendering the advancing means inoperative at selected intervals and for periods of predetermined duration.

20. A machine for making link mesh comprising the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of the supplies, for feeding wire therefrom to the link forming tools, means for controlling the action of the wire feeding devices to cause the wire to be fed to the tools in a predetermined order of succession, a throw-off device for rendering the said control means inoperative throughout the formation of a selected number of links, and means for bringing the throw-off means into action at selected intervals.

21. A machine for making link mesh comprising the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of the supplies, for feeding wire therefrom to the link forming tools, an element having pattern control areas disposed thereon in accordance with a predetermined pattern, means under the control of these areas for causing a selected wire feeding device to become operative while the others remain inoperative, actuating means for causing the areas to be brought successively into operative position in correspondence with the operation of the link forming tools, a throw-off device operated by the power driven mechanism of the machine for controlling the actuating means whereby a single area controls the formation of a group of links of predetermined number, and automatic means for bringing the throw-off device into action at selected intervals during the progress of the link forming operation.

22. In a machine for making link mesh, the combination of a support for a piece of mesh, link forming tools, means for actuating the tools to add links to the piece of mesh, a plurality of supplies of wire, a plurality of devices, one for each supply, for feeding wire from the supplies to the link

forming tools, pattern control means actuated in accordance with the operation of the link forming tools for controlling the action of the wire feeding means to cause the wire to be fed to the tools from the supply in a predetermined order of succession, an automatic throw-off device for modifying the action of the pattern control means to cause a succession of links to be made of wire drawn from a single supply, and means actuated in accordance with the action of the link forming tools for bringing the automatic throw-off device into action at selected intervals.

23. In a machine for making link mesh, the combination with a support for a piece of mesh, link forming tools and means for actuating the tools to incorporate links in a piece of mesh, of a plurality of supplies of wire, a plurality of devices, one for each supply for feeding wire from the supplies to the tools an element having a series of color control areas disposed thereon in accordance with a pattern, means for moving the element to cause the areas to be brought successively into effective position, one for each operation of the link forming tools, a member movable to different positions of rest determined by the areas and in each such position of rest operable to cause one of the wire feeding devices to feed wire while the others are held inactive, and automatic means for modifying the action of the moving means to cause a single area to remain in effective position throughout the formation of a plurality of links.

24. In a machine for making link mesh, the combination with a support for a piece of mesh, link forming tools and means for actuating the tools to incorporate links in the piece of mesh, of a plurality of supplies of wire, a plurality of devices, one for each supply, for feeding wire from the supplies to the tools, a chain having a series of color control blocks disposed thereon in accordance with a pattern, means for moving the chain to cause the blocks to be brought successively into effective position, one for each operation of the link forming tools, a member movable to different positions of rest determined by the blocks and in each such position of rest operable to cause one of the wire feeding devices to feed wire while the others are held inactive, and an automatic throw-off device brought into action upon the completion of a predetermined number of links and operable to modify the action of the chain moving means to cause a single block to be held in operative position throughout the formation of a predetermined group of links.

25. In a machine for making link mesh, the combination with a support for a piece of mesh, link forming tools and means for actuating the tools to incorporate links in

the piece of mesh, of a plurality of supplies of wire, a plurality of devices, one for each supply, for feeding wire from the supplies to the tools, a chain having a series of color control blocks disposed thereon in accordance with a pattern, means for moving the chain to cause the blocks to be brought successively into effective position, one for each operation of the link forming tools, a member movable to different positions of rest determined by the blocks and in each such position of rest operable to cause one of the wire feeding devices to feed wire while the others are held inactive, an automatic throw-off device operable to render the chain moving means ineffective whereby a single block governs the formation of a predetermined group of links, and means operable upon the completion of a predetermined group of links for bringing the throw-off device into action.

26. In a machine for making link mesh, the combination with a support for a piece of mesh, link forming tools and means for actuating the tools to incorporate links in the piece of mesh, of a plurality of supplies of wire, a plurality of devices, one for each supply, for feeding wire from the supplies to the tools, a chain having a series of color control blocks disposed thereon in accordance with a pattern, means for moving the chain to cause the blocks to be brought successively into effective position, one for each operation of the link forming tools, a member movable to different positions of rest determined by the blocks and in each such position of rest operable to cause one of the wire feeding devices to feed wire while the others are held inactive, an automatic throw-off device operable to render the chain moving means ineffective whereby a single block governs the formation of a predetermined group of links, and means operable once per row of links in the piece for bringing the throw-off device into action.

27. In a machine for making link mesh, the combination with a support for a piece of mesh, link forming tools and means for actuating the tools to incorporate links in the piece of mesh, of a plurality of supplies of wire, a plurality of devices, one for each supply, for feeding wire from the supplies to the tools, a chain having a series of color control blocks disposed thereon in accordance with a pattern, means for moving the chain to cause the blocks to be brought successively into effective position, one for each operation of the link forming tools, a member movable to different positions of rest determined by the blocks and in each such position of rest operable to cause one of the wire feeding devices to feed wire while the others are held inactive, a throw-off plate, means for advancing the throw-off plate with a step-wise movement, means controlled

by the throw-off plate for rendering the chain moving means ineffective whereby a single block controls the formation of a group of links, and means operable upon the completion of a predetermined group of links for bringing the advancing means for said plate into action.

28. In a machine for making link mesh, the combination with a support for a piece of mesh, link forming tools and means for actuating the tools to incorporate links in the piece of mesh, of a plurality of supplies of wire, a plurality of devices, one for each supply, for feeding wire from the supplies to the tools, a chain having a series of color control blocks disposed thereon in accordance with a pattern, means for moving the chain to cause the blocks to be brought successively into effective position, one for each operation of the link forming tools, a member movable to different positions of rest determined by the blocks and in each such position of rest operable to cause one of the wire feeding devices to feed wire while the others are held inactive, a selector disc moved in correspondence with the operation of the link forming tools, an element carried by the disc and brought into effective position once per rotation of the latter, a throw-off plate, means for advancing the throw-off plate, brought into action whenever the member on the selector disc is in operative position, and means controlled by the throw-off plate for rendering the chain moving means inoperative whereby a single block is held in effective position throughout the formation of a group of links.

29. In a machine for making link mesh, the combination with a support for a piece of mesh, link forming tools and means for actuating the tools to incorporate links in the piece of mesh, of a plurality of supplies of wire, a plurality of devices, one for each supply, for feeding wire from the supplies to the tools, a chain having a series of color control blocks disposed thereon in accordance with a pattern, means for moving the chain to cause the blocks to be brought successively into effective position, one for each operation of the link forming tools, a member movable to different positions of rest determined by the blocks and in each such position of rest operable to cause one of the wire feeding devices to feed wire while the others are held inactive, a rotary selector disc, an element on the disc, means for rotating the disc with a step by step movement, the disc making a complete rotation upon the completion of a row of links in the mesh, a throw-off plate, means controlled by the plate for modifying the action of the chain advancing means to cause a single block to remain in effective position throughout the formation of a group of links, and means rendered operative by the

element on the selector disc for advancing the throw-off plate by one step.

30. In a machine for making link mesh, the combination with a support for a piece 5 of mesh, link forming tools, and means for operating the tools to add links successively to the piece of mesh, of a plurality of supplies of wire, a plurality of devices, one for each supply, for feeding wire from the supplies to the tools, an element having a series 10 of color control areas arranged thereon according to a pattern, a control bar movable to different positions of rest, means cooperating with the areas for determining the position of rest of said bar, means controlled by the bar for rendering the wire feeding devices effective, means for moving the element to cause the areas to be brought into effective position, and automatic means for 15 rendering the moving means ineffective at selected intervals.

31. In a machine for making link mesh, the combination with a support for a piece 20 of mesh, link forming tools and means for operating the tools to add links successively to the piece of mesh, of a plurality of supplies of wire, a plurality of devices, one for each supply, for feeding wire from the supplies to the tools, an element having a series 25 of color control areas arranged thereon according to a pattern, means for moving the element to cause the areas to be brought successively into effective position, one element 30 for each link being formed, a control bar movable to different positions of rest, a plurality of members, one for each wire feeding device, one of which is actuated by the control bar in each of its positions of rest to cause its associated wire 35 feeding device to become operative, means connected with the control bar for moving the latter to positions of rest determined by the control areas on the element, and an automatic throw-off device operable to render 40 the means for moving the element ineffective, whereby a single area will control the formation of a plurality of links.

32. In a machine for making link mesh, the combination with a support for a piece 45 of mesh, link forming tools, and means for operating the tools to add links successively to the piece of mesh, of a plurality of supplies of wire, a plurality of devices, one for each supply, for feeding the wire from the supplies to the tools, an element having a series 50 of color control areas arranged thereon according to a pattern, means for moving the element to cause the areas to be brought successively into effective position, one element 55 for each link being formed, feeler means brought into contact with the area in such effective position, a member moved to different positions of rest in accordance with the positions taken by said feeler means 60 when in contact with said areas, and in each

such position of rest operable to render one of the wire feeding devices effective while the others remain ineffective, and means for controlling the action of the said moving means to cause a single area to be held in 70 effective position throughout the formation of a group of links.

33. In a machine for making link mesh, the combination with a support for a piece 75 of mesh, link forming tools, and means for operating the tools to add links successively to the piece of mesh, of a plurality of supplies of wire, a plurality of devices, one for each supply for feeding the wire from the supplies to the tools, an element having a series 80 of color control areas arranged thereon according to a pattern, means for moving the element to cause the areas to be brought successively into effective position, one element for each link being formed, feeler means brought into contact with each area in such effective position, a member moved to different positions of rest in accordance with the positions taken by said 85 feeler means when in contact with said areas, and in each such position of rest operable to render one of the wire feeding devices effective while the others remain ineffective, a throw-off device for rendering the moving means ineffective, whereby a single area is 90 caused to control the production of a plurality of links, and means for bringing the throw-off mechanism into action at selected intervals.

34. In a machine for making link mesh, the combination with a support for a piece 100 of mesh, link forming tools, and means for operating the tools to add links successively to the piece of mesh, of a plurality of supplies of wire, a plurality of devices, one for 105 each supply, for feeding the wire from the supplies to the tools, an element having a series of color control areas arranged thereon according to a pattern, means for moving the element to cause the areas to be brought 110 successively into effective position, one element for each link being formed, feeler means capable of being given different positions of adjustment as determined by the color control areas, means for bringing said 115 feeler means into cooperating relation with said areas, a member movable to different positions of rest as determined by the positions of adjustment of said feeler means, and in each such position of rest operable 120 to render one of the wire feeding devices effective while the others are held inactive, and means for controlling the action of said moving means whereby a single area is 125 caused to remain in effective position throughout the formation of a group of links.

35. In a machine for making link mesh, the combination with a support for a piece 130 of mesh, link forming tools, and means for

operating the tools to add links successively to the piece of mesh, of a plurality of supplies of wire, a plurality of devices, one for each supply, for feeding the wire from the supplies to the tools, an element having a series of color control areas arranged thereon according to a pattern, means for moving the element to cause the areas to be brought successively into effective position, one element for each link being formed, feeler means capable of being given different positions of adjustment as determined by the color control areas, means for bringing said feeler means into cooperating relation with said areas, a member movable into cooperating relation with said areas, a member movable to different positions of rest as determined by the positions of adjustment of said feeler means, and in each such position of rest operable to render one of the wire feeding devices effective while the others are held inactive, an automatic throw-off device for controlling the action of said element moving means whereby a single area is held in effective position throughout the formation of a group of links, and means for bringing the throw-off device into action at selected intervals.

36. In a machine for making link mesh, the combination with a support for a piece of mesh, link forming tools, and means for operating the tools to add links successively to the piece of mesh, of a plurality of supplies of wire, a plurality of devices, one for each supply, for feeding the wire from the supplies to the tools, an element having a series of color control areas arranged thereon according to a pattern, means for moving the element to cause the areas to be brought successively into effective position, one element for each link being formed, a pair of relatively adjustable feeler members brought into cooperating relation with the area in effective position, a slide on which the feeler members are carried, means for reciprocating this slide once for each operation of the link forming tools, a member movable to different positions of rest as determined by the relative positions of adjustment of said feeler members, this element in each position of rest being operable to render one of the wire feeding devices effective while the others remain inactive, and automatic means for controlling the means for moving said element whereby a single area remains in effective position throughout the formation of a group of links.

37. In a machine for making link mesh, the combination with a support for a piece of mesh, link forming tools, and means for operating the tools to add links successively to the piece of mesh, of a plurality of supplies of wire, a plurality of devices, one for each supply, for feeding the wire from the

supplies to the tools, an element having a series of color control areas arranged thereon according to a pattern, means for moving the element to cause the areas to be brought successively into effective position, one element for each link being formed, a pair of relatively adjustable feeler members, a slide on which the feeler members are carried, means for reciprocating this slide once for each operation of the link forming tools to bring the feeler members into cooperating relation with the area in effective position, a member movable to different positions of rest as determined by the relative positions of adjustment given said feeler members by said areas, this element in each position of rest being operable to render one of the wire feeding devices effective while the others remain inactive, a throw-off device for rendering the means for moving said element inoperative whereby a single pattern control area remains in effective position throughout the formation of a group of links, and means for bringing the throw-off means into action at selected intervals.

38. In a machine for making link mesh, the combination with a support for a piece of mesh, link forming tools, and means for operating the tools to add links successively to the piece of mesh, of a plurality of supplies of wire, a plurality of devices, one for each supply, for feeding the wire from the supplies to the tools, an element having a series of color control areas arranged thereon according to a pattern, means for moving the element to cause the areas to be brought successively into effective position, one element for each link being formed, a pair of feeler members capable of being given different relative positions of adjustment upon their contact with said areas, a slide on which the feeler members are carried, means for reciprocating the slide in correspondence with the operation of said link forming tools to bring the feeler members into contact with the area in effective position, a bar movable to different positions of rest and in each such position capable of rendering one of the wire feeding devices operative while the others remain inactive, and connections between the slide and the bar for causing the bar to be moved to a position of rest determined by the relative positions of adjustment given said feeler members by said areas.

39. In a machine for making link mesh, the combination with a support for a piece of mesh, link forming tools, and means for operating the tools to add links successively to the piece of mesh, of a plurality of supplies of wire, a plurality of devices, one for each supply, for feeding the wire from the supplies to the tools, an element having a series of color control areas arranged thereon according to a pattern, means for moving

- the element to cause the areas to be brought successively into effective position, one element for each link being formed, a pair of feeler members capable of being given different relative positions of adjustment upon their contact with said areas, a slide on which the feeler members are carried, means for reciprocating the slide in correspondence with the operation of said link forming tools.
- 5 10 to cause the feeler members to contact with the area in effective position, a bar movable to different positions of rest and in each such position capable of rendering one of the wire feeding devices operative while the others remain inactive, connections between the slide and the bar for causing the bar to be moved to a position of rest determined by the relative positions of adjustment of said feeler members, and automatic throw-off
- 15 20 means for rendering the means for moving said element ineffective at selected intervals, whereby a single area thereon determines the wire to be employed in the formation of a plurality of links.
- 25 40. In a machine for making link mesh, the combination with a support for a piece of mesh, link forming tools, and means for operating the tools to add links successively to the piece of mesh, of a plurality of supplies of wire, a plurality of devices, one for each supply, for feeding the wire from the supplies to the tools, a rotatable element having an endless succession of pattern control areas arranged thereon according to a pattern, means for moving the element with a step by step movement in accordance with the operation of the link forming tools, each step causing one of the areas to be brought into effective position, a member movable to different positions of rest and in each such position operable to render one of the wire feeding devices operative while the others remain inactive, means controlled by the areas on said element for moving the member to its different positions of rest, and means operable at selected intervals during the progress of the link forming operation for rendering the moving means for said element ineffective whereby a single area determines the position of said member throughout the formation of a plurality of links.
- 45 50 55 60 65 41. In a machine for making link mesh, the combination with a support for a piece of mesh, link forming tools, and means for operating the tools to add links successively to the piece of mesh, of a plurality of supplies of wire, a plurality of devices, one for each supply for feeding the wire from the supplies to the tools, a rotatable element having an endless succession of pattern control areas arranged thereon according to a pattern, means for moving the element with a step by step movement in accordance with the operation of the link forming tools, each step caus-
- ing one of the areas to be brought into effective position, a member movable to different positions of rest and in each such position operable to render one of the wire feeding devices effective while the others remain inactive, means controlled by the areas on said element for moving the member to its different positions of rest, a throw-off device for putting the means for moving said element out of action, whereby a single area determines the position of said member throughout the formation of a plurality of links, and means for bringing said throw-off device into action at selected intervals during the progress of the link forming operation.
- 70 75 80 85 90 95 100 105 110 115 120 125 130 42. In a machine for making link mesh, the combination with a support for a piece of mesh, link forming tools, and means for operating the tools to add links successively to the piece of mesh, of a plurality of supplies of wire, a plurality of devices, one for each supply, for feeding the wire from the supplies to the tools, a rotary support, a chain engaging said support and carrying a plurality of pattern control blocks arranged thereon in a predetermined order of succession, means for giving the support a step by step rotary motion, each step serving to bring one of the blocks into effective position, a member movable to different positions of rest and in each such position operable to render one of the wire feeding devices effective while the others remain inactive, and means connected with said member and cooperating with said blocks to cause the member to be moved to positions of rest as determined by said blocks.
43. In a machine for making link mesh, the combination with a support for a piece of mesh, link forming tools, and means for operating the tools to add links successively to the piece of mesh, of a plurality of supplies of wire, a plurality of devices, one for each supply for feeding the wire from the supplies to the tools, a rotary support, an endless chain engaging the support, a receptacle through which the chain passes for taking up the slack of the chain, this receptacle having a length less than the slack of the chain contained therein, means for giving the support a step-wise rotary movement to cause the blocks thereon to be brought successively into effective position, one block at each step, a member movable to different positions of rest and in each such position operable to render one of the feeding devices operative while the others remain inactive, and means connected with said member and cooperating with said blocks to cause the member to be moved to positions of rest as determined by said blocks.
44. In a machine for making link mesh, the combination with a support for a piece of mesh, link forming tools, and means for

operating the tools to add links successively to the piece of mesh, of a plurality of supplies of wire, a plurality of devices, one for each supply, for feeding the wire from the supplies to the tools; a rotary support, a chain engaging the support and having a plurality of pattern control blocks arranged thereon in accordance with a pattern, means for giving the support a step by step rotation at each period of rest of which one of the blocks on the chain lies in effective position, a member movable to different positions of rest and in each such position serving to render one of the wire feeding devices operative while the others are held inactive, means movable into contact with the block in effective position, and operable under the control of such block to cause the member to be moved to a position of rest determined by the block, a throw-off plate having depressions formed in its surface, an arm receivable in said depressions and in such position operable to render ineffective the means for producing the rotary movement of said support, and means for moving the plate to present the depressions to said arm at selected intervals.

45. In a machine for making link mesh, the combination with a support for a piece 30 of mesh, link forming tools, and means for operating the tools to add links successively to the piece of mesh, of a plurality of supplies of wire, a plurality of devices, one for each supply, for feeding the wire from the supplies to the tools, a rotary support, a chain engaging the support and having a plurality of pattern control blocks arranged thereon in accordance with a pattern, means for giving the support a step by step rotation, at each period of rest of which one of the blocks on the chain lies in effective position, a member movable to different positions of rest and in each such position serving to render one of the wire feeding devices operative while the others are held inactive, means movable into contact with the block in effective position, and operable under the control of such block to cause the member to be moved to a position of rest determined by the block, a throw-off plate having depressions formed in its surface, an arm receivable in said depressions and in such position operable to render ineffective the means for producing the rotary movement of said support, and means for producing a step-wise movement of said plate, each step corresponding to the completion of a predetermined group of links.

46. In a machine for making link mesh, 60 the combination with a support for a piece of mesh, link forming tools, and means for operating the tools to add links successively to the piece of mesh, of a plurality of supplies of wire, a plurality of devices, one for each supply, for feeding the wire from the

supplies to the tools, a rotary support, a chain engaging the support and having a plurality of pattern control blocks arranged thereon in accordance with a pattern, means for giving the support a step by step rotation 70 at each period of rest of which one of the blocks on the chain lies in effective position, a member movable to different positions of rest and in each such position serving to render one of the wire feeding devices operative 75 while the others are held inactive, means movable into contact with the block in effective position and operable under the control of such block to cause the member to be moved to a position of rest determined 80 by the block, a throw-off plate having depressions formed in its surface, an arm receivable in said depressions and in such position operable to render ineffective the means for producing the rotary movement of said support, a selector disc, means for rotating the disc with a step by step movement in correspondence with the formation of links, a depression formed in said disc, and means 85 contacting with the disc and brought into action by said depressions for advancing the throw-off plate by one step.

47. In a machine for making link mesh, the combination with a support for a piece 95 of mesh, link forming tools, and means for operating the tools to add links successively to the piece of mesh, of a plurality of supplies of wire, a plurality of devices, one for each supply, for feeding wire from the supplies to the tools, an element having a succession of pattern control areas arranged thereon in a predetermined order, means for moving the element to cause the areas to be brought successively into effective position, a guide member for guiding the wire being fed to the link forming tools, this member being movable to different positions of adjustment determined by the supply from which the wire is being drawn, a member 100 movable to different positions of rest and in each such position operable to render one of the wire feeding devices effective and to position the block to cause that wire to be properly fed to the tools, means for moving the member to its different positions of rest under the control of a pattern control area, and a device for rendering ineffective the means for moving the element bearing the pattern control areas whereby one of said areas remains in effective position throughout the formation of a plurality of links.

48. A machine for making link mesh which comprises the combination of a support for a piece of mesh, link forming tools, power driven mechanism for giving the tools and the piece of mesh a step by step relative movement and for operating the tools in the periods of rest of this movement, a plurality of supplies of wire, a plurality of devices, one for each of these sup-

- plies, for feeding wire therefrom to the link forming tools, a movable guide block having passages therethrough for each of the wires, a member having a succession of pattern control areas arranged thereon in a predetermined order, means for moving the member to cause the areas to be brought successively into effective position, means controlled by the area in effective position for rendering 10 one of the wire feeding devices effective and for causing the positioning means to place the block in position to guide to the tools the wire being fed by said feeding device, and means for rendering the element moving 15 means ineffective at selected intervals whereby a single area will control the formation of a predetermined group of links.
49. In a machine for making link mesh of wires of different kinds, the combination of 20 a plurality of supplies of wire, a plurality of rotary feeding members, one for each of the supplies, these members lying with their axes parallel and in a row, means for actuating the members, and automatic means for 25 controlling the actuating means.
50. In a machine for making link mesh of wires of different kinds, the combination of 30 a plurality of supplies of wire, a plurality of pairs of driven rolls, each of said pairs of rolls engaging and serving to feed one of said wires, these pairs of rolls being placed side by side with their axes parallel, means for actuating each of the pairs of rolls, and actuating means for controlling the action of 35 the actuating means.
51. In a machine for making link mesh of wires of different kinds, the combination of 40 a plurality of supplies of wire, a plurality of pairs of driven rolls, one pair for each of said supplies, these rolls being formed to grip and feed one of the wires and all of the pairs lying side by side with their axes parallel, all of the wires passing between the axes of each pair of rolls, means for rotating 45 each of the rolls, and automatic means for controlling the action of the rotating means.
52. In a machine for making link mesh, the combination with a support for a piece of 50 mesh, link forming tools, and means for operating the tools to add links successively to the piece of mesh, of a plurality of supplies of wire, a plurality of devices, one for each supply, for feeding the wire from the supplies to the tools, an element having pattern control members of different characteristics mounted thereon in a predetermined order of succession, means for giving the element a step by step movement, each step serving to 55 bring one of the members into effective position, and a second element movable to different positions of rest and in each such position operable to render one of the feeding devices effective while the others remain inactive, and means connected with said sec- 60 ond element and cooperating with said members on the element to cause the second element to be moved to positions of rest as determined by the members on the first element. 70
53. A machine for making link mesh, comprising the combination of a support for a piece of mesh, link-forming tools, power driven mechanism for giving the tools and the piece of mesh a step-by-step relative movement and for operating the tools in the periods of rest of this movement, a plurality of supplies of wire, a plurality of devices, one for each of the supplies, for feeding wire therefrom to the tools, and means for controlling the action of the wire feeding devices to cause the wire to be fed from the supplies in a predetermined order of succession and including an endless chain having pattern control members arranged thereon according to a predetermined pattern, and a receptacle for receiving the slack of the chain. 75
54. A machine for making link mesh comprising the combination of a support for a piece of mesh, link-forming tools, power driven mechanism for giving the tools and the piece of mesh a step-by-step relative movement and for operating the tools in the periods of rest of this movement, a plurality of supplies of wire, a plurality of devices, one for each of the supplies, for feeding wire therefrom to the tools, and means for controlling the action of the wire feeding devices to cause the wire to be fed 80 from the supplies in a predetermined order of succession, and including an endless chain having pattern control members arranged thereon according to a predetermined pattern, and a receptacle for receiving the slack of the chain. 85
55. A machine for making link mesh which comprises a support for a piece of mesh, means for forming links intermeshing with the links of the piece of mesh, a plurality of supplies of wire, feeding means associated with each of said supplies for feeding wire therefrom, a ratchet and pawl for operating each of said feeding means, means for moving the pawls to advance the ratchets upon the formation of each link, a rod associated with each pawl and movable to render said pawl effective or ineffective, a member movable to different positions of rest and operable to determine the position of said rods, and means for controlling the position of said member according to a predetermined pattern. 90
56. A machine for making link mesh which comprises a support for a piece of mesh, means for forming links intermeshing with the links of the piece of mesh, a plu- 95

rality of supplies of wire, feeding means associated with each supply, a ratchet and pawl for actuating each of said feeding means, means for moving the pawls upon the formation of each link, a rod associated with each pawl and movable to render the pawl effective or ineffective, a member having means thereon for controlling the action of said rods, and means operable in accordance with a predetermined pattern for controlling the action of said member.

57. A machine for making link mesh which comprises a support for a piece of mesh, means for forming links intermeshing 15 with the links of the said piece of mesh, a plurality of supplies of wire, means for feeding wire from these supplies to the link-forming means, and mechanism for controlling the action of said wire feeding means 20 including a ratchet and pawl associated with each feeding means, a cam member movable to different positions of rest and in each of said positions operable to render one of said pawls effective while maintaining the others ineffective, and means for determining the 25 position of rest of said cam member in accordance with a predetermined pattern.

58. In a machine for making link mesh containing links of different kinds of wire 30 the combination of a plurality of supplies of wire, feeding means associated with each supply and including a ratchet and pawl, a rock shaft connected to all the pawls and effective to move the pawls to advance their 35 ratchets, and a member movable to different positions of rest in accordance with a predetermined pattern and in each such posi-

tion operable to render one pawl effective while maintaining the others ineffective.

59. In a machine for making link mesh 40 containing links of different kinds of wire, the combination of a plurality of supplies of wire, means for feeding wire from each supply and including a ratchet and pawl, a rock shaft connected to each of the pawls 45 and effective to move the pawls to advance the ratchets, and means for determining the order in which the wire is fed from the supplies, including a member movable to different positions of rest, and means operable 50 by the member in each of said positions for moving all but one of the pawls out of effective relation to their ratchets.

60. In a machine for making link mesh, 55 the combination of link-forming means, means for feeding wire thereto from a plurality of supplies, a block for guiding the wire so fed to the link-forming means, this block having a plurality of channels, a ratchet and pawl associated with each of 60 said wire feeding means, means for swinging the pawls continuously, and means for determining the order of succession in which wire is fed in accordance with a predetermined pattern and including a member movable to different positions of rest and effective 65 in each position to render one pawl effective while maintaining the others ineffective and also for moving the block to different positions in accordance with the supply 70 from which wire is being fed.

In testimony whereof I affix my signature.

FRED HARRIS LYNDS.

CERTIFICATE OF CORRECTION.

Patent No. 1,666,940.

Granted April 24, 1928, to

FRED HARRIS LYNDS.

It is hereby certified that error appears in the printed specification of the above numbered patent requiring correction as follows: Page 21, line 34, claim 50, for the word "actuating" read "automatic"; and that the said Letters Patent should be read with this correction therein that the same may conform to the record of the case in the Patent Office.

Signed and sealed this 29th day of May, A. D. 1928.

(Seal)

M. J. Moore,
Acting Commissioner of Patents.
